POWDER MIXING AND SPRAYING
DEVICE

Frederick R. Maurer, Detroit, Mich.

Application September 23, 1932, Serial No. 634,516

4 Claims. (Cl. 299—84)

This invention relates to powder mixing and spraying devices, and more particularly to a spraying device especially designed to be incorporated in a water pipe or hose line through which water under pressure is delivered, to enable the mixing of powders with such water, and spraying of the same in the form of a solution or mixture. An important object of this invention is the provision of a powder mixing and spraying device which enables the spraying of insecticides mixed with water from the nozzle of an ordinary garden hose.

A further object is the provision of such a spraying device the parts of which may be principally housed within the hose itself in such manner that the hose constitutes a powder container.

Still another object is the incorporation in such a device of improved adjusting means enabling varying the quantity of powder mixed with the water flowing therethrough.

Still another object lies in the provision of a mixing device which may be secured to a hose line either at its end or at some medial point, or in a water pipe, which device incorporates a relatively large powder container arranged outside the water line, powder in which may be fed under pressure into the water flowing through the line.

Other objects and advantages will be apparent from the following description, wherein reference is made to the accompanying drawings illustrating preferred embodiments of my invention, and wherein similar reference numerals designate similar parts throughout the several views.

In the drawings:

Figure 1 is a sectional view of the end of a garden hose, showing one form of my invention installed therein and fragmentarily showing a hose nozzle in side elevation;

Figure 2 is an end view of the body portion of the powder mixing unit;

Figure 3 is a sectional view thereof taken substantially on the line 3—3 of Figure 2 and looking in the direction of the arrows;

Figure 4 is a side view of the adjusting screw;

Figures 5 and 6 are side and end views respectively of the water tube coupling pipe;

Figures 8 and 9 are side and medial sectional views of a packing ring;

Figures 10 and 11 are similar views of a screen member employed to prevent clogging of the device by lumps of powdered material;

Figure 12 is a view partly in section and partly

in side elevation of a somewhat modified form of the invention, showing the same also adapted to use in connection with a garden hose, but with an outside powder container affixed thereto, showing a hose nozzle attached to the device; 60

Figure 13 is a detail section taken substantially on the line 13—13 of Figure 12;

Figure 14 is a detail sectional view taken substantially on the line 14—14 of Figure 12;

Figure 15 is a plan view of a lock washer; 65

Figure 16 is an end view similar to Figure 2 of the mixing unit employed in this form of my invention;

Figure 17 is a sectional view thereof similar to Figure 3, taken substantially on the line 17—17 70 of Figure 16;

Figure 18 is a side view similar to Figure 4 of the adjusting screw employed in this form of my invention;

Figures 19 and 20 are plan and diametrical 75 sectional views respectively of the garden screen employed in this embodiment;

Figure 21 is a view partly in cross section and partly in side elevation of another somewhat modified form of the invention which is adapted 80 to be inserted in a water line at any point;

Figure 22 is a sectional view taken substantially on the line 22—22 of Figure 21;

Figures 23 and 24 are plan and longitudinal 85 sectional views respectively of the guard screen employed in this embodiment;

Figures 25 and 26 are end and medial sectional views respectively of the mixing unit;

Figure 27 is a side view of the adjusting screw, and 90

Figure 28 is a longitudinal section of the water-feeding tube.

Referring now to the drawings: Reference character 30 designates a rubber garden hose, carrying at its end an exteriorly threaded coupling member 32, shown as of conventional design. To the coupling 32 an adjustable spray nozzle as 34 is frequently connected, to enable variation of the character of the water jet. Between the hose coupling 32 and the nozzle coupling 36 is a gasket, usually in the form of a rubber washer 38. This assembly, without my inserted spraying device, will be seen to comprise the familiar garden hose and nozzle of the type generally used for watering purposes about 95 homes and small gardens. To enable persons gardening on a small scale, or growing fruit or ornamental trees or bushes to spray their growing things with powdered insecticide solutions mixed with water without the necessity of mix- 100 105 110

ing the powder with the water by hand and then forcing the solution or mixture from the nozzle of a special spraying device by means of a hand or special pump, and to provide similar convenient spraying means for those desiring to spray disinfectants, as in treating livestock, and for other purposes. I provide the mixing device shown installed in the hose in Figure 1, in conjunction with which the hose itself may be used as a powder container, whereupon the device will mix the powder with the water flowing through the hose in such manner that there is ejected from the nozzle a regulatably proportioned insecticide mixture.

15 The body portion 40 of the mixing device is a relatively small cylindrical metallic member, formed as best shown in Figures 2 and 3 and carrying at its upper extremity a flange 42, which flange is enlarged by an auxiliary flange ring 44. 20 The flange ring 44 may be adapted to encircle the body member 40 beneath the flange, to enable the suspension of the device within the end of the hose by clamping the flange formed by the portions 42-44 between the coupling 32 25 and gasket 38. An aperture, the central portion of which is designated 46, extends substantially axially through the body of the mixing device, being countersunk or otherwise enlarged at its rear extremity, as at 48, to form a funnel-shaped 30 inlet portion into which the powder is fed. The aperture is also formed with a reduced and tapered front portion 50, one side of which is open to the partly cylindrical adjoining chamber 52 in which the cylindrical valve portion 35 54 of an adjusting screw 56 is adapted to move to change the effective size of the outlet portion 50 of the aperture in a readily apparent manner. The stem of the valve is threaded in a tapped continuation 58 of the bore 52. On the 40 opposite side of the aperture 46, also in the body of the mixing member, is a rearwardly opening bore 60 having a laterally opening orifice 62 communicating with the portion 46 of the central powder feeding aperture and also having an 45 inclined communicating bore 64 terminating in the front face of the device adjacent the powder feeding bore 50. The aperture 64 is designed to discharge a jet of water angularly from the mixing device and toward the powder extruded 50 from the orifice 50, in such manner that they will be quickly and thoroughly mixed within the chamber furnished by the portion 37 of the nozzle coupling by the turbulence caused by the angular and forceful delivery of the jet of water 55 from the bore 64. The water discharged into the central portion 46 of the powder tends to keep the central powder passage 46 and powder discharge orifice 50 clear while washing powder from the outlet. Tightly fitted in the bore 60 is 60 a rearwardly projecting tube or pipe section 66 having a hole 68 in its side adapted to align with the opening 62 in the side of the bore 60 when the tube is installed, as shown in Figure 1.

The rearwardly projecting portion of the tube 65 66 forms a coupling to which a relatively small flexible rubber tube 70 may be attached by slipping the same thereover. The rubber tube 70, coupling tube 66 and connecting passages form a water by-pass. The unit is installed in the 70 hose by removing the nozzle and pushing the small tube 70 part way down thereinto, a short length of the small tube being left hanging out of the end of the hose, with the mixing unit attached thereto. The hose is then compressed, 75 as by stepping on it, at a point nearer its nozzle

end than the container end of the inner tube 70. The hose 30 is then filled with the desired insecticide powder which may be hydrated lime, Paris green, arsenate of lead, or the like, or a mixture. The powder may be inserted in the hose with the aid of a funnel, the end of which may be easily inserted in the hose if the mixing unit is allowed to hang free outside the end of the hose at the end of the two or three extra inches of the tubing 70 left at the nozzle end in the manner described. After the hose has been filled with powder, the mixing unit is slid into and clamped in place by means of the nozzle coupling in the manner shown. When the water is turned on, the pressure upon the rear surface of the powder column tends to force the powder through the central aperture 48-46 and from the orifice 50, while a quantity of the water is delivered directly to the nozzle through the tubes 70 and 66 and bore 64, the water so discharged mixing with the powder being extruded from the orifice 50 in the manner described. A certain amount of the by-passed water also passes through the aligned orifices 62-68 connecting the water and powder passages within the mixing device, such water helping to force the powder from the nozzle and by its pressure loosening the same in mixing therewith. When the valve portion 54 of the adjusting screw is near the small outer end of the orifice 50, the effective size of the latter is reduced, and the amount of powder which can be forced thereinto to be mixed with the by-passed water is restricted, while when this valve portion is moved inwardly to the position in which it is shown in dotted lines in Figure 1, the orifice is opened and a larger area made effective.

Covering the rear of the mixing unit may be a guard screen as 72, which may, as shown, be formed as a cap adapted to fit over the enlarged counterbored portion 48 and prevent the passage of lumps of the powdered material into the mixing device. The screen may of course be perforated, as at 74 and 76, for the passage therethrough of the stem of the adjusting screw 56 and the coupling tube 66 respectively.

In Figures 12 to 20 inclusive I have shown a somewhat modified form of my invention in which a powder container, external to the end of the hose to which the entire device is attached, is incorporated with a special coupling member which carries means for affixing a powder jar or can thereto and for affixing the assembly to the end of the hose, together with a control valve and a mixing device for mixing the powder and water, means for exerting pressure upon the powder and means for attaching a hose nozzle to the device. In Figure 12 reference character 130 indicates the hose, and 78 designates the body of the device, which forms 135 a coupling member for the hose, the powder jar 80 and the nozzle 134. Water under pressure is delivered to the base of the powder mass within the jar 80 through the water passage 82 and tube 84. Within the shell 78 is arranged a mixing unit similar in its general construction and mode of operation to that described in connection with the first embodiment. The body of the device is designated 140, and the frusto-conical portion 148 of the powder aperture therein is arranged over the mouth of the jar 80 in such manner that the pressure of the water behind the powder forces the latter through the central aperture in the mixing device 145 in a manner analogous to the operation of the 150

similar portions of the first described hose inserted mixer. Water under pressure is delivered to the central portion 146 of the mixing device through the passage 162, which functions similarly to the aperture 62 of the first described embodiment, as does the water delivery bore 164, through which water is discharged from the mixing device in such manner that it is instantaneously mixed with the powder extruded through the orifice 150 in like fashion. An adjusting screw 156 is also provided, by means of which the rate of powder delivery may be regulated by turning the screw by means of a screw driver, (when the nozzle 134 is removed) and the space 137 above the mixing device, as well as the space within the rear portion of the nozzle, provides a mixing chamber in which the turbulence caused by the angular and forceful delivery of the water jet may similarly cause mixture of the water and powder. If a glass jar is used it is of course possible to see the amount of powder remaining therein at all times.

If desired a controlling valve 86 may be provided, adapted to be moved by the finger of the operator. For this purpose the finger piece 88 is provided, formed as an integrally bent over section of the valve stem 90, which finger piece is adapted to travel in a guide slot 92 formed in the body of the device as shown in Figure 12. The tendency of water pressure to maintain the valve in seated position may be augmented by compression spring 94, encircling the valve stem, and the stem may travel in a central aperture in the cork 96 which seals the aperture through which the stem passes. The cork may be retained in the enlarged upper portion 98 of the valve stem apertures by means of a spring washer 100, the form of which is best shown in Figure 15, locked in a suitable internal annular groove in the apertured portion 98 above the cork. This lock washer also forms a seat for one end of the compression spring 94, the other end of which bears upwardly against another washer 99 maintained in position upon the stem 90 by the bend in its outer extremity. A suitable screen, as 172, may of course be arranged between the jar mouth and the powder inlet 148 of the mixing device, to guard the latter against being clogged by lumps.

Another somewhat modified form of my invention is shown in Figures 21 to 28 inclusive. This device will at once be seen to be analogous to the construction shown in the embodiment last described, but adapted to be inserted at any point in a hose or pipe line, remote from the nozzle if desired, and to feed powder into the water stream. The body portion 278 of the device may be formed as a screw cap 280, which may be of glass if desired, and a water inlet coupling member 230 may be carried by the top thereof and adapted to be screwed to a faucet or to the end of a water pipe. Through the water passage 282 water is delivered to the pressure pipe 284 which extends to a point adjacent the bottom of the jar in a manner similar to the arrangement of the pipe 84 of the last described embodiment, while a connecting passage 270 delivers water directly to the mixing unit 240 through the coupling tube 266 which discharges into the water jet passage 264 opening adjacent the powder outlet 250 in like manner. Water is also fed through the side connecting aperture 262 for preliminary mixture with the powder

in the central section 246 of the powder orifice in the mixing unit, in a manner similar to the operation of these portions of the first described embodiment. A powder feeding adjusting screw 256 may also be provided, and the downwardly opening tapered aperture 287 in the cap 278 arranged to connect the mouth of the jar with the powder inlet 248 of the mixing unit in a manner which will be readily apparent. A screen, as 272, may of course be arranged across the open lower end of the orifice 287 to similarly prevent the entrance of lumps of the powdered material into the mixing unit.

My improved mixing device is also utilizable for any spraying of powder in conjunction with an air hose connected to any suitable source of air under pressure, as a hand or mechanical pump. The air of course functions in substantially the same manner as the water in forcing the powder from the nozzle.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

What I claim is:

1. In combination with a flexible hose through which fluid under pressure is adapted to be delivered, a coupling carried by the end of the hose and a nozzle member removably secured to the coupling, means for mixing powder with fluid delivered by the hose, including a quantity of powder within the hose, a mixing device arranged between the powder mass and the nozzle, and a relatively small flexible tube secured to the mixing unit at one end and extending back into the hose away from the nozzle and open at its other end to provide a fluid by-pass through which fluid may be delivered to a point adjacent the nozzle without forcing it to percolate through the powder.

2. In combination with a flexible hose through which fluid under pressure is adapted to be delivered, a coupling carried by the end of the hose and a nozzle member removably secured to the coupling, means for mixing powder with fluid delivered by the hose, including a quantity of powder within the hose, a mixing device secured in the end of the hose and having a portion clamped between the nozzle and coupling members, said mixing device having powder and fluid delivery passages extending therethrough, and means connecting a fluid passage with a point in the hose farther from the nozzle than the powder mass extends, comprising a relatively small tube connected to the mixing unit and extending and opening into the hose.

3. A fluid and powder mixing device for mixing powder with a stream of fluid under pressure, comprising a body having separate and terminally converging powder and fluid delivery passages therein terminating in adjacent powder and fluid outlets and connected by a by-pass spaced from their termini, the powder passage having a portion varying in cross sectional area approaching its outlet, and a screw threaded member having a body portion within and movable longitudinally of said portion of the powder passage of variant cross-section, to enable varying the effective size of the powder outlet.

4. In combination with a water hose, means for mixing powder with water delivered there-

through, comprising a body member coupled to the hose line and having an inlet opening therein through which it may receive water from the hose line, said body member having also an outlet opening and appurtenant coupling portion to which a nozzle is adapted to be secured, a third opening and coupling portion, a powder container coupled to the third opening, said body member having passages therein connecting said three openings, and mixing means carried by said body portion and comprising a chambered portion having terminally convergent jet apertures.
